CLAIM

The ornamental design for a basketball, as shown and described.

DESCRIPTION

FIG. 1 is a top perspective view of basketball;

FIG. 2 is a first side view thereof;

FIG. 3 is a second view thereof;

FIG. 4 is a bottom view thereof;

FIG. 5 is a top view thereof;

FIG. 6 is a front view thereof; and,

FIG. 7 is a rear view thereof.

The ornamental design that is claimed is shown in solid lines in the drawings. The dashed lines shown in FIGS. 1 through 7 are included for the purpose of illustrating environmental elements only and form no part of the claimed design.

1 Claim, 7 Drawing Sheets
